ABSTRACT: A portable desk or table that has a support firmly attached to the body of the user and a work surface pivotally and slidably attached to the support. These two areas of adjustability allow the work surface to adjust to any size user in a sitting as well as a standing position without necessitating a change of the mounting of the support member on the user.

PORTABLE BODY-MOUNTED DESK

The present invention relates to a portable body-mounted desk that has a high degree of adjustability and simplicity that has not heretofore been known in the field of body-mounted desks. The adjustability is brought about by the work surface being pivotally mounted on the body-mounted support and the pivot point being vertically adjustable on the support. There is also an adjustable length support leg attached between the body support and the work surface to permit the angle and height of the work surface to be fixed. In addition to the versatility of adjustment the work surface can be folded flat against the support so that a person can perform other duties between the periods when it is desired to use the desk.

It is, therefore, an object of this invention to provide a portable desk that is body-mounted for stability.

It is a further object of this invention to provide a portable body-mounted desk that has vertical and angular adjustability.

It is a further object of this invention to provide a portable body-mounted desk that can fold flat to permit the wearer to perform other duties without removal of the desk.

It is a still further object of the invention to provide an adjustable body-mounted desk whose unique but simple construction allows economical production.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a perspective view of the desk in an operative position.

FIG. 2 is a front plan view of the desk in its retracted position.

FIG. 3 is a rear perspective view of the device in the position of FIG. 2.

FIG. 4 is a sectional view of the device taken substantially along the line 4-4 of FIG. 1.

FIG. 5 is a sectional view taken substantially along the line 5-5 of FIG. 4.

FIG. 6 is a sectional view taken substantially along line 6-6 of FIG. 4.

FIG. 7 is an enlarged view of the latch mechanism on the adjustable work surface support.

FIG. 8 is a sectional view taken substantially along the line 8-8 of FIG. 7.

FIG. 9 is a side view of the device in the retracted position of FIGS. 2 and 3.

Referring now to the drawings the desk is indicated generally by the numeral 10, with the support assembly designated 12 and the work surface assembly or table 14. The support assembly comprises a rigid support plate 16 with an adjustable neck encircling strap 18, with buckle 19 thereon, attached to the upper edge thereof and an adjustable waist strap 20, with buckle 21 thereon, attached to the opposite side edges. The straps 18 and 20 are fixed at one end 22 and 24, respectively, and detachably connected by the use of hook assemblies at the other ends 26 and 28, respectively, to permit ease of donning the device. The straps 18 and 20 are easily adjusted by the buckles 19 and 21, respectively, to accommodate any size person. The front face of support plate 16 has inwardly facing U-shaped tracks 30, 30 mounted parallel to each other along the side edges thereof to slidably mount block 32 therebetween. A screw 34, with an enlarged head 36 is threadedly engaged with an opening through the block 32 and bears against a metal strip 38 mounted on the surface of plate 16, to hold the block in any position along the tracks 30, 30. Attached to the lower edge of block 32 is an abutment or mount 40 on which is mounted a hinge 42 that mounts the work surface assembly 14 to the support assembly 12. The abutment is of sufficient height so that the work surface 44 can lay on top of head 36 in a plane parallel to the support plate 16 when in folded or collapsed position. A further abutment 46 is mounted atop of plate 16 and is sufficient in height

to maintain the work surface 44 in the aforementioned plane parallel to plate 16.

5 A support leg assembly 48 maintains the work surface 44 at any angle of adjustment relative to the support plate 16. The leg comprises a tube 50 and a rod 52 slidable thereinto. The tube is pivotally mounted at 54 to abutment 56 on plate 16. The rod is similarly pivoted at 58 to abutment 60 on work surface 44. A collar 64 is threaded onto tube 50 to slidably receive the rod 52 therethrough, and to provide a threaded opening for the locking screw 66. The screw 66 thus projects through collar 64 and tube 50 to releasably engage rod 52 and tube 50 and fix them relative to one another. The screw 66 has a pin 68 depending from the underside of the knurled head thereof to be engaged by collar 70 which slides along tube 50. The screw 66 can thereby be prevented from loosening, by engagement of pin 68 with the collar extension 71, with a resultant drop of the work surface. The end of tube 50 and rod 52 are mounted on the abutment 56 and 60, respectively, to permit the work surface to fold upwardly into a plane parallel to support 16, as mentioned hereinbefore.

20 A paper holder, a clamp 72, consists of a crosspiece 74 with U-shaped ends 76 that engage the edge of work surface 44 in sliding engagement therewith. Antifriction pads 78 placed between crosspiece 74 and work surface 44 permits smooth sliding therebetween. On the back of the ends 76 and attached thereto are bow-shaped leaf springs 80. The springs 80 maintain the crosspiece 74 in firm contact with surface 44 on the pads 78. Journaled for pivotal movement on the ends 76 is a 25 U-shaped paper bar 82 with rollers 84 thereon. Coil springs 86 are attached at each end of the crosspiece with one end thereof attached near leaf springs 80 and at the other end on bar 82 well above its journal point on end 76. Thus the bar 82 will be resiliently urged against the work surface 44 whether it 30 be in a position above the crosspiece when not in use, see FIG. 4, or in a position below the crosspiece 74, when in use.

To utilize the desk, the user puts the strap 18 around his neck and strap 20 around his waist adjusting the straps to firmly mount support plate 16 against his body. The screws 66 and 35 36 are then loosened and the work surface is pivoted out of its stored position, shown in FIGS. 3 and 9, to a desirable working position, such as that shown in FIGS. 1 and 4. When the desired position is achieved the screw 36 is tightened to fix the pivot point between support plate 16 and work surface 44, and screw 66 is tightened, collar 70 moved in position to prevent loosening of leg 48.

35 The portable desk as described herein can find utility for students, laboratory or research workers, soldiers, artists or anyone needing a firm work surface when a table or desk is not convenient. The simplicity of construction and the full adjustability as provided thereby, allow the desk to adapt to any size person or any angle or height orientation relative to the user's body.

50 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

I claim:

1. A portable body-mounted desk comprising an upstanding support panel including front and rear sides and being adapted for support from a person's body with the rear side opposing and resting upon the lower chest and upper stomach regions of the wearer of the desk, a mount slidably supported from said support panel for adjustable vertical shifting over the front side of said support panel, means operatively associated with said mount and support panel, for releasably retaining said mount in adjusted position relative to said support panel, a table panel including one marginal edge portion thereof pivotally secured to said mount for oscillation relative thereto about a horizontal axis generally paralleling said support panel between an extended position with the free edge portion of

said table panel projecting outwardly from the front side of said support panel and a collapsed position with the free edge portion of said table panel swung upwardly and said table panel closely overlying the front face of said support panel, and an elongated adjustable length support leg assembly having one end thereof pivotally secured to the underside of said table panel at a point spaced outwardly from said horizontal axis and the other end thereof pivotally supported from said support panel outwardly from the front side thereof and below said horizontal axis, said support leg assembly being extendable to an effective length sufficient to extend from said other end thereof to said point when said table panel is in its collapsed position, said support leg assembly including means operative to secure said leg assembly in adjusted extended position.

2. The combination of claim 1 wherein said table panel includes a paper holder slidably supported therefrom for adjustable movement along said table panel toward and away from said axis, said paper holder including a pivoted spring urged bail provided with rollers journaled therefrom for rota-

tion about axes generally paralleling said axis and biased into rolling contact with the upper surface of said table panel.

5. The combination of claim 1 wherein said support panel includes an elongated upstanding forwardly facing center portion thereof defining a wear surface, the first mentioned means comprising a setscrew threadedly secured through said mount and abuttingly engaged with said wear surface.

10 10. The combination of claim 1 wherein said support panel includes means defining upstanding parallel channels opening toward each other and in which the opposite side edge portions of said mount for slidingly received.

15 15. The combination of claim 1 wherein said support panel includes an elongated upstanding forwardly facing center portion thereof defining a wear surface, the first mentioned means comprising a setscrew threadedly secured through said mount and abuttingly engaged with said wear surface, said table panel, when in said collapsed position, overlying said setscrew and generally paralleling said support panel.
